UNITED STATES PATENT OFFICE.

CLEN S. HUMPHREY, OF BROOKLYN, NEW YORK.

POWDER BOX.

Application filed June 15, 1926. Serial No. 116,180.

This invention relates to containers and has particular reference to a container for powder and a puff or applicator for applying the same.

5 The invention broadly comprehends a powder box including a body, a removable outer cover, and means arranged within the open end of the body to permit of sifting of the powder therefrom, and to constitute a 10 supporting means for an applicator puff, which is maintained in closed relation to the sifting means to prevent accidental spillage of the powder.

More specifically the invention comprehends a container for powder including a body having an open upper end, a friction slip cover adapted to engage thereover, and an inner friction tray telescopically mounted within the open end having sifter openings 15 and constituting means for supporting a puff of a sufficient size to fill the tray, whereby when the outer cover is applied the puff is maintained in a position to close the sifter openings for preventing spillage of the powder therefrom.

A further object of the invention resides in the provision of a powder box including a body having an open upper end, a removable cup-shaped tray mounted within the upper open end having sifter openings, an applicator puff filling the tray, and an outer telescopic cover for closing the open end and maintaining the puff impinged against the bottom of the tray for closing the sifter 30 openings against accidental spillage of the powder.

The invention aims as a still further object to provide a powder box of the character set forth which is comparatively simple in its 35 construction, inexpensive to manufacture, and which is highly efficient in its purpose.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications 45 which properly fall within the scope of said claims may be resorted to when found expedient.

In the drawings—

Figure 1 is a plan view of a powder box constructed in accordance with the inven-

tion, with the outer cover removed and the applicator puff partly broken away;

Fig. 2 is a vertical transverse sectional view taken approximately on the line 2—2 of Fig. 1, with the outer cover in superposed relation.

Referring to the drawings by characters of reference, 10 designates the body of a powder container which is closed by a bottom wall 11 and which is open at its upper end, the edge of the upper end being rolled inwardly to form a bead. A substantially cup-shaped tray 13 formed with an outwardly projecting peripheral flange 14, is designed to be telescopically associated with 65 and frictionally fitted within the upper open end, the inward movement of the same being limited by the flange 14. The tray is provided with a bottom wall 15 having apertures 16 constituting sifter openings for discharging the powder from the body of the container. The tray also serves as a means for receiving an applicator puff 17 which is of a size to approximately fit the tray. The cover or lid 18 is adapted to telescope over 70 the upper open end and frictionally engage the same and said cover further operates to completely house the puff and impinge its bottom face against the upper face of the tray bottom 15 so that the sifter openings 75 16 are closed against accidental spillage and wasting of the powder when the cover or lid is thus applied. When the cover or lid is removed, it is obvious that the powder may be sifted through the sifter openings upon 80 the face of the puff and thus applied.

From the foregoing it will thus be seen that a powder box has been devised which in addition to serving as a container for the powder, is equipped with means to facilitate 95 the sifting of the same therefrom, which means also acts as a supporter for an applicator puff and which applicator puff also functions as a means for sealing the sifter openings against accidental discharge of the 100 powder when the outer cover or lid is applied.

What is claimed is:

1. A powder box, including a body having an open upper end, a friction cover therefor 105 adapted to telescopically fit over said upper end, a tray adapted to frictionally and telescopically fit within said upper open end, said tray having sifter openings, and an applicator puff adapted to be arranged within 110

the tray and of a sufficient size to fill said tray, whereby when the friction cover is applied the face of the puff covers and closes the sifter openings.

- 5 2. A powder box, including a body having an open upper end, a friction cover therefor adapted to telescopically fit over said upper end, a tray adapted to frictionally and telescopically fit within said upper open end, 10 said tray having sifter openings, and an applicator puff adapted to be arranged within

the tray and of a sufficient size to fill said tray, whereby when the friction cover is applied the face of the puff covers and closes the sifter openings, the edge of the upper 15 open end of the body being rolled inwardly to provide a bead within which the tray engages and the tray formed with an outwardly projecting annular flange of slightly less diameter than the outer diameter of the upper 20 end of the body.

CLEN S. HUMPHREY.
